Des. 192,579
Patented Apr. 10, 1962

192,579

SPICE DISPENSER

B. Rampinelli-Schwarz, Egelgasse 31, Bern, Switzerland, and Jean Walter, Zollikofen-Bern, Switzerland

Filed Dec. 7, 1960, Ser. No. 63,141

Term of patent 7 years

(Cl. D58—6)

FIG. 1

FIG. 2

FIG. 3

FIG. 4

FIG. 5

FIGURE 1 is a perspective view of a spice dispenser embodying our new design;

The side not shown is substantially the same as the side shown.

We claim:

The ornamental design for a spice dispenser, substantially as shown and described.
